his Attorney.

UNITED STATES PATENT OFFICE.

HARRY LEVINE, OF CHICAGO, ILLINOIS.

DOOR-LOCK.

1,283,535.

Specification of Letters Patent.

Patented Nov. 5, 1918.

Application filed May 15, 1916. Serial No. 97,723.

To all whom it may concern:

Be it known that I, HARRY LEVINE, a subject of the Czar of Russia, and a resident of the city of Chicago, county of Cook, and 5 State of Illinois, have invented certain new and useful Improvements in Door-Locks, of which the following is a specification.

My invention relates to improvements in door latches, and has for its object the provision of an improved construction of this character, especially adapted for permitting a partial opening of the door, preparatory to a full opening thereof.

The invention consists in the combinations and arrangements of parts herein-after described and claimed.

The invention will be best understood by reference to the accompanying drawings forming a part of this specification, and 20 in which,

Figure 1 is a horizontal section taken through the swinging edge of a door, illustrating a door latch embodying my invention, in position of use,

25 Fig. 2, an interior face view of the latch, and

Fig. 3, a section taken on line 3—3 of Fig. 1.

The preferred form of construction, as 30 illustrated in the drawings, comprises a latching frame 4 let into and secured to the door frame 5 of an ordinary swinging door 6, in operative relation with the swinging edge of said door. The inner side 7

35 of the latching frame 4 is provided with an extension 8 passing across the swinging edge of the door, when in closed position, and bent angularly around the inner corner of the door frame 5, as indicated in Fig. 1.

40 A latching bar 9 is slidably mounted in frame 4, and is normally held in retracted position by means of a tension spring 10 secured to said frame and to said bar, to permit of inward sliding of the bar against the tension of said spring. The inward end 11 of the bar 9 is offset, as indicated, to pass

45 the swinging edge of the door 6, and is provided with a latching opening or notch 12 adapted to receive the latch bar 13 of an ordinary spring latch 14 secured to the inner side of the door 6. A notch or opening 15 is formed in the extension 8 to register with the opening or notch 12, and a guiding or

50 guard tongue 16 is arranged opposite the opening 15 to compel the latch bar 13 to clear

the extension 8, when the door is swung inwardly.

By this arrangement, it will be observed, that upon inward swinging of the door 6, the latching bar 9 will be withdrawn from 60 the frame 4 for a certain distance, thus permitting a view through the partially open door, but preventing the complete opening of the door. When it is desired to completely open the door, the latch bar 13 may 65 be readily released from the notch 12 when desired.

A positive latch 17 is slidably mounted on the angularly bent portion of extension 8 by means of rivets 18 engaging through 70 a slot 19 therein. Latch 17 is provided with an operating bead or lip 20 and so arranged that the edge 21 thereof may be readily placed in the path of movement of the extension 11, so as to positively lock the door 75 in closed position, and prevent even a partial opening thereof.

While I have illustrated and described the preferred form of construction for carrying my invention into effect, this is capable 80 of variation and modification without departing from the spirit of the invention. I, therefore, do not wish to be limited to the precise details of construction set forth, but desire to avail myself of such variations and 85 modifications as come within the scope of the appended claims.

Having described my invention what I claim as new and desire to secure by Letters Patent is:

1. The combination with a door frame and a door therefor, of a latching frame let into said door frame in operative relation with the swinging edge of said door; a latching bar slidably mounted in said latching frame to move with said door, there being a latching opening in the outer end of said latching bar adapted to receive a latch, there being also an opening in the frame to register with the opening in the latching bar; and a guiding tongue opposite said opening in the frame arranged to compel a latch to clear the same, substantially as described.

2. The combination with a door frame 105 and a door therefor, of a latching frame let into said door frame in operative relation with the swinging edge of said door; a latching bar slidably mounted in said latching frame to move with said door, there 110

being a latching opening in the outer end of said latching bar adapted to receive a latch, there being also an opening in the frame to register with the opening in the latching bar; and a slidable latch slidably mounted on said latching frame and arranged to engage the end of said latching bar, substantially as described.

In testimony whereof I have signed my name to this specification in the presence 10 of two subscribing witnesses.

HARRY LEVINE.
